United States Patent

Des. 241,848
Patented Oct. 12, 1976

241,848

AIR FRESHENER OR SIMILAR ITEM

Georg Schimanski, Breckerfeld, Germany, assignor to Globol-Werk GmbH, Neuburg (Danube), Germany

Filed Apr. 29, 1975, Ser. No. 572,804

Term of patent 14 years

Int. Cl. D23—04

U.S. Cl. D23—150

FIG. 1

FIG. 4

FIG. 1 is a perspective view of an air freshener showing my new design in the closed position;

FIG. 2 is a perspective view in the partially open position;

FIG. 3 is a sectional view taken on line 3—3 of FIG. 1; and

FIG. 4 is a sectional view similar to FIG. 3, but in the fully open position.

I claim:

The ornamental design for an air freshener or similar item, as shown and described.
